DETECTOR MECHANISM FOR CAPPING MACHINES

Robert J. Stewart, Baltimore, Md., assignor to
 Crown Cork & Seal Company, Inc., Baltimore,
 Md., a corporation of New York

Application December 7, 1939, Serial No. 308,097

8 Claims. (Cl. 226—84)

The present invention relates to a detector mechanism for capping machines and, more particularly, to a mechanism for indicating any failure in the supply or application of caps.

Container handling apparatus of the type in which caps, for example, of the crown type, are applied to bottles or other containers ordinarily include a moving capping head which, in one position, receives a cap from a cap supply chute and, in another position, applies the cap to a container.

If the supply of caps in the cap chute becomes exhausted, or if through some momentary fault a cap is not placed in a capping head prior to the movement of that capping head toward a bottle, at least one bottle will be left uncapped. At the present time such a condition can only be guarded against by constant observation of the bottles coming from the machine. In most plants, an attendant is stationed some distance from the filling machine to carefully inspect bottles passing directly in front of him. By the time that an uncapped bottle reaches this attendant, a number of uncapped bottles may be in the line between the filling machine and the inspector, all of which will have to be re-passed through the capping mechanism. Also, in many plants mixing machines which turn the container vertically endwise are placed between the filling machine and the inspector. If an uncapped container moves into the mixing machine, its entire contents will be wasted when the container is inverted.

The principal object of the present invention is to provide a mechanism which will give an alarm or stop the machine in the event that the supply of caps to a capping head becomes depleted or if a particular container does not have a cap applied thereto. The invention may be so installed upon a capping machine that it will be effective in case either one or both of the above difficulties should occur.

Another object of the invention is to provide a mechanism for the above purposes which will be simple in construction and operation and which can be readily applied to the usual capping machine.

A still further object of the invention is to provide a cap feed detector which will not interfere with the feeding of caps to the capping heads.

Still another object of the invention is to provide a detector mechanism of the nature described above which is electrically controlled

through a circuit of such arrangement that the operation of the device will be entirely positive.

Other objects and advantages of the invention will be apparent from the following drawings wherein:

Figure 1 is a front elevation of the mechanism for detecting the absence of a cap upon a bottle, the view being taken in the direction of the arrow A in Figure 3.

Figure 2 is a horizontal sectional view through the upper housing of the device of Figure 1.

Figure 3 is a diagrammatic view showing the circuit provided in the event that mechanisms of the present invention are to be applied to a capping mechanism for indicating a failure in the supply of caps in the cap chute and also the absence of a cap from bottles after they have moved beneath the capping head, and

Figure 4 is a detail vertical section on the line 20 4—4 of Figure 3.

The numeral 10 designates the work table of a filling machine having a detector mechanism 11 provided thereon for the purpose of checking the presence of caps upon bottles which have moved beneath the capping mechanism. The mechanism 11 is positioned at a point on the work table past which bottles will move after they have been through the capping mechanism, this point preferably being adjacent the outfeed dial 12 of the machine, that is, the dial which moves the bottles from the capping mechanism to the usual straight line conveyor 13 which conducts the bottles from the machine. The usual guide plate surrounding the outfeed dial 12 is designated by the numeral 14 in Figure 1.

The mechanism 11 is positioned above the path of movement of bottles with the outfeed dial 12, the mechanism being mounted upon a hollow post 15 fixed to the table 10 and through which post the necessary electrical connections may extend. A horizontally extending casing 16 projects from the post 15 outwardly over the periphery of the outfeed dial 12, the casing 16 preferably comprising a flat base plate 17 to which a cover 18 of inverted box form is secured by means of machine screws such as 19.

A pair of collars 20 formed of insulating material are mounted in apertures in the lower wall of the base plate 17 and a hollow metal sleeve 21 is rotatably positioned in each collar 20, the sleeves extending above and below the collars. On their portions within the housing 16 each sleeve 21 has a lever 22 of insulating material secured thereto by means of a machine screw 23

which is threaded into a socket in the arm and through aligned holes in the sleeve 21. Each lever 22 at its rearward end carries an angled contact member 24 which is secured to the lever by the screw 23, screw 23 also serving as a binding post for a conductor wire, the wire to one lever being designated by the numeral 25 and the wire to the other lever being designated by the numeral 26. The opposite or free arms of the contacts 24 face a spring pressed bridging contact 27 against which the two contacts 24 normally bear as shown in Figure 2 due to action of a coil spring 22a which joins the free ends of the levers 22.

The bridging contact 27 is mounted upon a small stud 28 projecting from a block 29 of insulating material, and the stud has a light spring positioned thereon between its head and the rear surface of the contact 27. The block 29 is secured to a plate 30 carried by a second stud 31 in a base block 32 extending upwardly from the base plate 17 of the casing. A spring 33 is positioned on the stud 31 between the base block 32 and the plate 30, spring 33 being of somewhat greater strength than the spring provided on the stud 28. The base block 32 includes laterally extending flanges 34 by means of which it is secured to the base plate 17 by screws 34a. It will be observed from the above that the bridging contact 27 is supported from the base block 32 but is entirely insulated therefrom and also that the position of the bridging contact with respect to the base block as well as to the two contacts 24 may be varied by adjustment of the large stud 31, the adjustment being maintained by the spring 33. Stud 31 is accessible for adjustment through an aperture 35 in the side wall of the cover 18 normally closed by a small threaded cover plate as shown in Figure 2.

Below the base plate 17 of housing 16 the pivot sleeves 21 have plates 38 or brush members, i. e., contact members, secured thereto by radial pins 39 and at their outer ends the plates 38 carry metal blocks 40 preferably having bristles 41 extending from the same. As best shown in Figure 3, the brushes 38 are so angled that the bristles 41 will be arranged on a line extending substantially radially of the outfeed dial 12, or at least along a line transverse to the path of movement of the bottle.

It will be observed from the above that in the detector mechanism 11 the spring 22a connecting the two upper arms or levers 22 will normally draw the free ends of these arms toward each other with the result that the contacts 24 fixed to the opposite ends of the arms will be urged into engagement with the bridging contact 27. A circuit will therefore normally be closed between the conductor leads 25 and 26 and through the contacts 24 and bridging contact 27. Simultaneously, the lower and brush carrying arms 38 will be urged toward each other. Obviously, if the brush arms 38 are forced apart, the contact arms 22 will likewise swing apart against the action of the spring 22a so as to move the contacts 24 out of engagement with the bridging contact 27 to open the circuit between the leads 25 and 26.

Figures 3 and 4 illustrate a detector mechanism 45 applied to the cap supply chute of the capping mechanism. The numeral 46 designates a capping mechanism casting of the type provided with a plurality of reciprocable capping heads 47 rotating above a capping dial through which the

bottles move prior to their delivery to the outfeed dial 12. The numeral 48 indicates the usual cap supply chute having its lower end curved inwardly to be opposite the capping chamber 49 of each capping head 47 so that a cap C will be supplied to the capping chamber from the lower end of the chute as the head rotates past the chute.

The mechanism 45 illustrated in Figures 3 and 10 4 involves brush elements, i. e., contact elements, 50 positioned adjacent each side of the cap supply chute 48 with wire bristles 51 included in the brush elements extending into slots 52 formed in the rearward corners of the chute so that caps 15 moving downwardly through the chute will have their opposite edges or skirt portions come into contact with the inner ends of the bristles 51. The brush members 50 are of a length longitudinally of the chute substantially corresponding to 20 twice the diameter of a cap C as shown in dotted lines in Fig. 4 so that under normal circumstances two caps C may be in contact with the bristles 51. This will insure that the circuit will be maintained between the bristles 51 by at least one cap during the time when a lower cap is leaving the bristles while a second cap is entering between the same from above.

In order to insure that the caps will not become 30 lodged between the opposed bristles 51 and thereby stop the feeding of caps to the capping heads, continuous blasts of air are directed upon the interiors of caps which are between the bristles through tubes 53 connected to the usual air blast tube, not shown, which is positioned to direct air upon the caps in the lower part of the 35 chute to force them into the capping head. As is best shown in Figure 4, a sufficient number of air blast tubes 53 is provided to insure that caps will be subjected to an air blast during their 40 entire passage between the bristles 51. The bristles 51 are, of course, so arranged that they will not come into contact with any metal portion of the cap chute 48.

The circuit to which the detector mechanisms 45 45 11 and 45 are connected receives power through two main leads 60 and 61. Main 60 is connected by a lead 62 with the lead 25 of the mechanism 11. The lead 26 of mechanism 11 is connected as 50 diagrammatically shown in Figure 3 with leads 63 and 63a extending to one brush 50 of the detector mechanism 45. The other brush 50 of detector mechanism 45 joins a lead 64 connected to one side of the coil 65 of an electro-magnet or control device. The other side of coil 65 is connected to a lead 66 which extends to a fixed contact 67 ordinarily connected by a movable contact 68 with a second fixed contact 69 connected by a lead 70 to the other main lead 61. The movable contact 68 is carried by a bell crank 71 55 suitably connected to an armature, not shown, controlled by the coil 65 and so long as the coil is energized, the movable contact 68 will be held upward to bridge the fixed contacts 67 and 69.

Bell crank 71 also carries, insulated from contact 68, two other contacts 74 and 75 facing in the opposite direction from contact 68. When the coil 65 is deenergized, as subsequently explained, contact 74 will bridge a contact 76 and a contact 77, while contact 75 will simultaneously 70 bridge two fixed contacts 78 and 79. Contact 76 is joined to upper fixed contact 69 by a lead 80 while its associated contact 77 is connected by a lead 81 to a resistor 82 in series with a lamp 83. The contact 78 of the other lower pair of fixed contacts is connected to lamp 83 by a lead 84 and

its associated contact 78 is connected by a lead 85 to lead 83 at a point in advance of the lead 83a.

When the circuit through the coil 65 is interrupted either by opening of the circuit in detector 45 or momentary opening of circuit through detector mechanism 11, the bell-crank or armature 71 will drop to cause contacts 74 and 75 to each bridge the opposed pairs of lower contacts. As a result current will flow through the lamp 83 and resistor, as hereinafter explained. If desired leads 80 and 81 may be connected in the lamp circuit to simultaneously actuate a relay to stop the motor of the capping mechanism.

In the operation of the apparatus, so long as caps C are moving downwardly in regular order through the cap supply chute 48 and so long as each bottle has a cap applied thereto by the capping mechanism, the series circuit through the detector mechanism and coil 65 will remain as illustrated in Figure 3. That is, the coil 65 will receive uninterrupted current and will be energized due to the fact that one or more caps will constantly bridge the bristles 51 of the brushes 50 of the detector mechanism 45 and a constant current will flow through the detector mechanism 11 which, like the detector mechanism 45, is in series with the coil 65.

The operation of the detector mechanism 11 is as follows: During the time that no bottle is passing through the mechanism, leads 25 and 26 will be joined for current flow by engagement of bridging contact 27 by contacts 24 as shown in Figure 2. When a bottle with a cap C applied thereto moves from the capping mechanism and the cap moves into engagement with the bristles 41 of the detector mechanism 11, a circuit will immediately be closed from lead 25 through the binding post 23 and sleeve 21 and thence through the arms 38 and bottle cap C to the opposite sleeve 21 and binding post connected to lead 26. When the full diameter of the bottle cap comes between the bristles 41, the arms 38 will be spread as indicated in Figure 3 with the result that the upper arms or levers 22 will also be spread and will turn with their pivot sleeves 21 in the insulating sleeves 20 so as to swing the contacts 24 out of engagement with the bridging contact 27. However, since a path for the current to the coil 65 has already been set up through the bottle cap, the supply of current to the coil will not be interrupted. The contacts 24, of course, again come into engagement with the bridging contact 27 before the cap C moves out of engagement with the bristles 41.

In the event that through some temporary failure a capping head does not receive a cap from the cap supply chute 48, with the result that the bottle subsequently moving beneath that capping head does not have a cap supplied thereto, the circuit through the detector mechanism 11 will be interrupted when the brush carrying arms are spread apart by the uncapped bottle. As a result, the coil 65 will be de-energized, permitting the armature 71 to drop so that the contacts 74 and 75 carried thereby will drop to respectively engage the lower pairs of fixed contacts 76-77 and 78-79. Because of this, and also because the circuit across the movable contact 27 of the detector mechanism 11 will again be closed as soon as the uncapped bottle has passed out of engagement with the bristles 41, a circuit will be established from main 60 through leads 62 and 25 and across bridging contact 27 to leads 26 and 63 and thence through lead 85 to contacts 79, 78 and 76 to lamp 83, resistor 82, lead 81 and con-

tacts 17, 14 and 76 to leads 80 and 78. The lamp 83 will thereby be illuminated to give an indication that a failure has occurred. If the succeeding bottles all have caps upon the same, the circuit last described will not be interrupted during the time that that bottle is spreading apart the brush carrying arms 38, so that the lamp 83 will remain lighted. However, should a succeeding bottle not have a cap applied thereto, lamp 83 will be momentarily unlighted when that bottle moves between the bristles 41.

Obviously, should the cap supply in chute 48 be exhausted, the circuit between brush members 50 will be opened and the lamp 83 will be illuminated as described above and because of the de-energization of coil 65. If a motor controlling relay is connected in the lamp circuit it will stop the motor. This latter control should be such as to prevent the motor from restarting when the lamp circuit is momentarily extinguished as by an uncapped bottle as described above.

In order to cause the circuit to be restored to its normal position, an attendant must press the reset button upon the armature 71 so as to cause the movable contact 68 to engage the upper fixed contacts 67 and 69 so that current will again flow through the electromagnet 65. It will be observed that the device cannot be reset or maintained in normal position unless each bottle moving through the detector mechanism 11 has a cap applied thereto, or unless a continuous stream of caps is moving between the bristles 51 of the detector mechanism 45.

The provision of the air blast nozzles 53 adjacent the contacts 50 of the detector mechanism 45 insures that the movement of caps through the chute will not be retarded by the bristles.

It will be apparent that in case it is not desired to use both detectors 11 and 45 upon a machine, either one may be used, in which case the circuit would be modified by closing the portion of the circuit occupied by the same.

If desired, coil 65 and the lamp circuit may be omitted and, instead, both of the detectors 11 and 45, or either detector, may be connected in series with a conventional magnetic switch coil in such manner that if the series circuit is broken by cap failure, the machine will be stopped.

The terminology used in the specification is for the purpose of description, the scope of the invention being indicated in the following claims.

I claim:

1. The combination in a capping mechanism of opposed contact elements in the cap supply chute and opposed contact elements in the path of containers moving from the capping mechanism, said respective opposed contacts adapted to be respectively bridged by caps moving through the cap chute and by caps upon containers, and a control device arranged in circuit with said respective contact devices.

2. The combination in a capping mechanism of opposed contact elements in the cap supply chute and opposed contact elements in the path of containers moving from the capping mechanism, said respective opposed contacts adapted to be respectively bridged by caps moving through the cap chute and by caps upon containers, a current responsive device in series with said contact devices, and a secondary control circuit controlled by said current responsive device.

3. The combination in a capping mechanism of opposed contact elements in the cap supply chute and opposed contact elements in the path of containers moving from the capping mechanism, said respective opposed contacts adapted to be respectively bridged by caps moving through the cap chute and by caps upon containers, a current responsive device in circuit with said contact devices, and a secondary control circuit adapted to be actuated upon interruption of current to said current responsive device.
4. In combination, means to move containers, a support, a pair of opposer contact members movably mounted on said support, means associated with said members to normally close a circuit between the same, a control device in circuit with said members, a second means carried by said members to contact with the cap upon a container to close an alternate circuit through the cap, said members being so arranged that said alternate circuit will be closed before the circuit through said first contact members is opened.
5. In combination, means to move containers, a support, a pair of pivoted arms carried on said support, said arms being provided with bottle cap engaging brushes at their free ends and contact members adjacent their pivots, the brush and contact of each arm being electrically connected, and a spring pressed contact adapted to normally engage said contacts, said contacts being arranged in a circuit including a control device.
6. In combination, means to move containers, a support, a pair of opposed contact members movably mounted on said support, means associated with said members to normally close the circuit between the same, and a control device in circuit with said members, said contacts being adapted to be separated by a capped container and the circuit normally through the same bypassed by the container cap.
7. In combination, a support, a pair of pivoted arms carried on said support, said arms being provided with bottle cap engaging brushes at their free ends and contact members adjacent their pivots, the brush and contact of each arm being adapted to be electrically connected, and a spring pressed contact adapted to normally engage said contacts, said contacts being adapted to be arranged in a circuit including a control device.
8. The combination in a capping mechanism, of a supply chute for skirted metal caps, a pair of resilient contact elements projecting into the chute sufficiently far to exert pressure upon the caps in a direction transversely of the chute, said resilient elements having a length longitudinally of the chute substantially corresponding to twice the diameter of the caps, a control circuit connected to each of said contacts, said circuit being normally closed by the engagement of caps with both contacts, and means to positively move caps by said contacts.

ROBERT J. STEWART.
